SECONDARY VACUUM SYSTEM

Lawrence R. Golladay, Wilkinsburg, and Charles H. Hodgkins, Pittsburgh, Pa., assignors to Westinghouse Electric and Manufacturing Company, a corporation of Pennsylvania

Application March 24, 1931. Serial No. 524,868

7 Claims. (Cl. 230—29)

Our invention relates to a secondary vacuum system and particularly to an oil-sealed pump and valve for a vapor electric device.

In the use of mercury-arc rectifiers, it has been customary to maintain the operative vacuum of the device by constantly pumping to eliminate any gas that might leak into, or be evolved in, the rectifier. The rectifier tank properly is preferably pumped by a mercury-vapor pump which 10 will work satisfactorily only against a back pressure of a few millimeters of mercury. Consequently, it is necessary to use a secondary vacuum system capable of discharging the pumped gases against atmospheric pressure. Originally, it was 15 necessary to run both the vapor pump and the secondary pump continuously in order to free the device of vapor.

Since the mechanical pump was subject to wear, this continuous operation proved uneconomical and, eventually, an interstage reservoir, as shown in Patent No. 1,716,160, was introduced between the vapor pump and the mechanical pump, and suitable pressure switches were provided, so that the secondary or mechanical pump 25 was only used a small fraction of the time that the rectifier was in operation.

The mechanical or secondary pumps are necessarily provided with sufficient clearance to allow mechanical movement of the parts. Consequently, when the pump was not in operation, it was mechanically almost impossible to prevent leakage through it. To prevent this leakage from reaching the rectifier, it is necessary to provide a vacuum-tight valve between the secondary 35 pump and the interstage reservoir. These valves have been very expensive to construct and their operation and maintenance required the services of one skilled in the handling of them.

We have discovered that the ordinary mushroom 40 room or poppet-type valve, while incapable of maintaining a vacuum-tight seal, when dry, will when oil sealed, maintain vacuum-tightness indefinitely. We have further found that the oil-sealed rotary-vane pump, in connection with a 45 poppet-type valve, will provide a very satisfactory, efficient and much less expensive secondary vacuum system than has heretofore been possible.

The vacuum system of our invention comprises 50 a rotary-vane type oil-sealed pump having means for flooding the pump with oil whenever it is not in operation and means for supplying sealing oil from the flooded pump to a normally closed poppet-type valve for maintaining a substantially 55 perfect vacuum seal for the secondary system.

The poppet valve is provided with a magnetic opening device which is energized by a speed-responsive switch which is so set that the poppet valve will not open until the rotary oil-sealed pump is operating at pumping speed. This insures that the secondary valve will be open only when the pump is operative and will prevent any possibility of leakage through the secondary system.

Other objects and advantages of our invention will be apparent from the following detailed description, taken in conjunction with the accompanying drawing, in which

Figure 1 is a view, partly in elevation and partly in section, of the essential elements of 70 our secondary system, and

Fig. 2 is a schematic diagram of our system.

The apparatus disclosed in the drawing comprises a mechanical pump, such as the vertically mounted rotary-vane pump 1 immersed in a reservoir 2 filled with oil. The pump 1 is directly connected to a driving motor 3 on the shaft 5 of which is mounted a centrifugal or speed-responsive switch 7 for controlling the vacuum valve presently to be described.

The rotary pump is provided with a discharge passage or conduit 9 in which is mounted a check valve 10 to substantially reduce the back-pressure and leakage through the pump. The discharge conduit 9 extends above the oil level 85 so that, when the pump is operating, it discharges directly to atmosphere without interference by the oil surrounding the pump. The discharge duct 9 is provided with a comparatively small vent 11 communicating with the oil in the reservoir 2 so that, when the discharge pressure of the pump is reduced, the discharge conduit will be flooded with oil to exclude the atmosphere 90 from the pump.

The pump is further provided with an inlet 95 passage 15 adapted to be connected to a vessel (not shown) intended to be evacuated, such as the interstage reservoir of a vapor electric device.

Since the oil-sealed pump is operated only intermittently, a vacuum valve is placed in the inlet passage 15. The body 16 of the valve is provided with a plurality of passages, one of which 17 communicates with the interstage reservoir and another 18 with the pump inlet passage. Still another 19 is provided through which 105 extends the stem 20 of an operating tappet for the valve element. A removable valve seat 24 is located in the valve body 16, said valve seat being provided with a substantially central opening 25 and a valve-stem guide 26. A mushroom 110

or poppet valve 28 extends through the valve seat and is supported by the stem guide 26. A spring member 29 is provided for maintaining the mushroom valve 28 in substantially vacuum-tight contact with the valve seat.

The portion of the valve tappet extending beyond the casing is enclosed in a vacuum-tight metallic bellows 30 which is provided with a contact element 32 for operating the valve stem.

10 The valve-actuating mechanism comprises an operating lever 34 pivoted on the valve body adjacent to the extending tappet and having a portion 35 adapted for contact with the tappet. A second lever 36, pivoted on the valve body, has 15 resilient driving contact 38 therewith so that the two levers, combined, act substantially as a bell crank for actuating the valve stem. The composite bell crank is actuated by an electromagnet 40 having a movable armature 41 pivoted to 20 the outer end of the actuating lever 36. The electromagnet is controlled by the speed-responsive switch 7 mounted on the pump shaft. In operation, the pump is started by pressure-responsive switches in the chamber to be evacuated 25 (not shown). As soon as the pump has reached pumping speed, the centrifugal switch 7 energizes the valve-operating magnet 40 which, through its bell-crank assembly, compresses the valve spring 29 to open the valve to permit evacuation 30 of the chamber by the rotary pump.

The pump discharges, through the exhaust conduit, to an open space in the oil reservoir surrounding the pump from which it is vented to atmosphere by the vent 45 in the top of the reservoir.

35 When the pump is operating, it will force the excess oil out of the pump and out of the exhaust passage, so that there is very little hindrance by the presence of the oil. However, 40 when the exhaust pump discharge pressure falls, oil from the reservoir will pass through the connection into the exhaust conduit, and, leaking past the check valve, will flood the pump proper, and leaking into the pump inlet passage will 45 reach the poppet valve and provide an oil seal for the same.

Upon resuming operation, the pump will first expel the oil contained therein but will leave a film of oil on all the working parts of the 50 pump, so that an effective oil seal will be maintained at all times.

While we have shown and described a specific embodiment of our invention, it is apparent that changes and modifications could be made therein without departing from the spirit and scope of our invention. We desire, therefore, that only such restrictions shall be imposed as are included in the appended claims or such as may be necessitated by the prior art.

60 We claim as our invention:

1. A secondary vacuum system for a vapor-electric device comprising a rotary oil-sealed pump, a discharge vent for discharging the pumped fluid to atmosphere, a check valve in 65 said vent, an oil reservoir adjacent to said pump, a connection between said reservoir and said vent for admitting oil thereto, said connection

being of less capacity than the vent, an inlet passage for connecting the pump to a vessel to be evacuated, a valve seat in said passage, a poppet valve for closing said passage, means for normally holding said valve in closed position, and magnetic means for opening said valve.

2. In combination, an oil-sealed mechanical vacuum pump, an oil reservoir, an exhaust for said pump extending through said reservoir, means for supplying oil to said pump from said reservoir, an inlet conduit for the pump, said inlet being adapted for connection to a vessel to be evacuated, and a spring-seated poppet valve for closing said inlet, said valve being sealed by oil leaking through said pump.

3. In combination, an oil-sealed mechanical vacuum pump, an oil reservoir surrounding said pump, an exhaust for said pump extending through the oil, means for supplying oil to said pump from said reservoir, an inlet conduit for the pump, said inlet being adapted for connection to a vessel to be evacuated, a poppet valve for closing said inlet, said valve being sealed by oil leaking through said pump, magnetic means for opening said poppet valve, and a centrifugal switch for energizing said magnetic means at a predetermined pump speed.

4. In a vacuum pumping system, a rotary oil-sealed pump, an inlet passage for said pump, a vacuum valve in said passage comprising a valve 105 casing, a seat therein, a mushroom valve element adapted to cooperate with said seat for closing said passage, the stem of said valve element extending outside of the valve, a metallic bellows for sealing the stem and magnetic means for 110 actuating the valve element.

5. A vacuum system comprising an oil-sealed rotary pump, a discharge for said pump, a check valve in said discharge for decreasing back pressure on the pump, and an oil reservoir surrounding the pump, said discharge having a vent for supplying oil for sealing the pump, an inlet passage for said pump adapted for connection to a vessel to be evacuated, an oil sealed valve in said inlet passage, magnetic means for opening said 115 valve, and means responsive to the speed of said pump for controlling the magnetic means.

6. A secondary vacuum system comprising a vertically disposed rotary pump, an oil reservoir enclosing said pump, a discharge conduit extending above the normal oil level in said reservoir, said conduit having a vent for admitting oil from 125 said reservoir to said conduit and a check valve between the conduit and the pump.

7. A secondary vacuum system comprising a 130 vertically disposed rotary pump, an oil reservoir enclosing said pump, a discharge conduit extending above the normal oil level in said reservoir, said conduit having a vent for admitting oil from said reservoir to said conduit and a check valve 135 between the conduit and the pump, an inlet conduit for said pump, a poppet valve in said conduit and magnetic means for opening said poppet valve.
